169,962

AIRPLANE

Vincent J. Burnelli, Great Neck, N. Y.

Application October 4, 1951, Serial No. 16,834

Term of patent 14 years

(Cl. D71—1)

To all whom it may concern:

Be it known that I, Vincent J. Burnelli, a citizen of the United States of America, residing at Great Neck, in the county of Nassau, State of New York, have invented a new, original, and ornamental Design for an Airplane, of which the following is a specification, reference being had to the accompanying drawing, forming part thereof.

Fig. 1 is a top plan view of an airplane, showing my new design.

Fig. 2 is front view in elevation of said airplane.

Fig. 3 is a side view in elevation of the airplane.

Fig. 4 is a side view in section of the airplane taken on line 4—4 of Fig. 2, and

Fig. 5 is a bottom plan view of the airplane.

I claim:

The ornamental design for an airplane, as shown.

VINCENT J. BURNELLI.
